UNITED STATES PATENT OFFICE.

GUNNAR SIGGE ANDREAS APPELQVIST AND EINAR OLOF EUGEN TYDÉN, OF STOCKHOLM, SWEDEN.

METHOD OF AND APPARATUS FOR CONCENTRATING ORE AND THE LIKE.

1,367,223.

Specification of Letters Patent.

Patented Feb. 1, 1921.

Application filed December 31, 1913. Serial No. 809,729.

To all whom it may concern:

Be it known that we, GUNNAR SIGGE ANDREAS APPELQVIST and EINAR OLOF EUGEN TYDÉN, subjects of the King of Sweden, 5 both residing at Stockholm, Sweden, have invented new and useful Improvements in Methods of and Apparatus for Concentrating Ore and the like, of which the following is a specification, reference being had to the 10 drawings accompanying and forming a part thereof.

This invention relates to a method of and an apparatus for concentrating ores and the like in a liquid by means of oil, tar, soap, 15 fat, hydrocarbons or the like. The object of the invention is to attain a speedy and at the same time as complete as possible separation of the metalliferous particles of the ore from the rock, and particularly to render 20 possible the concentrating of specular iron ore (non-magnetic ore), which so far has proved unfeasible in practice.

The new method consists mainly in that the ore and the oil, tar, or the like at the 25 moment of entering the liquid are subjected to a vigorous agitation by means of one or more streams of liquid under high pressure. When oil is used in practising this method it is preferably gasified by previous heating 30 in order to reduce the consumption of the same. On the other hand, when using tar, which has shown to great advantage in concentrating specular iron ore, it can be used in its common, liquid state, as it is very 35 difficult in practice to gasify tar. It is suitable to introduce the ore and the oil, etc., into the liquid in such a manner that they mix with one another just when entering the liquid.

40 In practising the new method we preferably use an apparatus comprising an injector or several injectors by means of which the gasified oil and the ore are introduced into a hopper of comparatively small size 45 so that the streams of water may effect a vigorous agitation therein; if desired the ore may be introduced into the small hopper separately from the gasified oil. From this hopper the mixture flows into a larger hopper 50 per where the separation takes place in such manner that the metalliferous particles will rise to the surface and the rock will sink to the bottom.

The accompanying drawings show in

Figures 1 and 2 diagrammatically two somewhat different forms of such an apparatus, partly in section, while Fig. 3 shows a section of a detail of the apparatus illustrated in Fig. 1.

In the drawings, 1 represents the larger 60 hopper, equipped with a surface spout 2 and with a drain 4, arranged to be closed by a valve 3. To the hopper 1 is attached a smaller hopper 5 in which the mixture is stirred.

According to Fig. 1, the ore as well as the gasified oil are both introduced into the hopper 5 through the nozzle 6 of an injector (Fig. 3). To this nozzle are connected the conduit 7 from the ore hopper 8, the gas 70 pipe 9 from the retort 10, and a pipe 11 from a pump 12. In the retort 10, which is placed within a suitable furnace 13, the oil, tar, etc. is gasified. When the oil, etc. is not to be used gasified the retort 10 and the furnace 13 will, of course, be omitted. By means of the pump 12 a powerful stream of water is driven through the nozzle 6 and carries along through injector action gasified oil from the pipe 9 and ore through the 80 conduit 7.

In the hopper 5 the stream of water will cause a vigorous agitation of the mixture, and the gasified oil will adhere to the metalliferous particles. The mass thus treated 85 flows into the larger hopper 1, in which the separation takes place, the surface part of the liquid together with the metalliferous particles flowing through the spout 2, while the rock sinks to the bottom and is removed 90 through the drain 4.

The modification illustrated in Fig. 2, which is intended for a larger production, is different from that above described mainly in that the ore and the gasified oil are introduced through separate conduits into the hopper 5. The ore passes from the ore-hopper 14 directly into the hopper 5 through the conduit 15, while the gas is introduced through the injector nozzle 16 by means of 100 a powerful stream of water. Still another water nozzle 17 is provided in order to obtain the necessary stirring, said nozzle 17 entering the hopper 5 in close proximity to the ore conduit 15. Otherwise this apparatus operates in the same manner as the apparatus shown in Fig. 1.

Having now described our invention and

in what manner the same is to be performed, we declare that what we claim and desire to secure by Letters Patent is:

1. The process of concentrating ore and the like consisting in introducing the ore and a selective agent into a body of separating liquid, agitating said ore and selective agent at the point of introduction into the separating liquid only by a stream of liquid under high pressure, and delivering the selective agent into contact with the ore in the agitating region.
  2. The process of concentrating ore and the like, which consists in projecting a stream of liquid into the ore and a selective agent in a common feed region, forcibly projecting the mixture thereby produced under impulse of the liquid stream into a restricted receptacle, and overflowing the thereby agitated mixture onto a body of flotation liquid.
  3. In an apparatus for concentrating ore and the like, the combination of a hopper of comparatively small volume, means for introducing the ore into the hopper, means for introducing a selective agent into the hopper near the point of introduction of the ore, means for introducing a stream of liquid under high pressure into the hopper near the point of introduction of the ore and the selective agent for agitating the same, and a flotation separating receptacle connected to said hopper and adapted to receive by overflow therefrom the mixture produced in the hopper.
  4. In an apparatus for concentrating ore and the like, the combination of a hopper of comparatively small volume, means for projecting a stream of liquid into the ore and selective agent at a common feed point in proximity to the hopper, the hopper being placed to receive the impact of the mixture under the impulse of the liquid stream, and a flotation separating receptacle connected to said hopper and adapted to receive by overflow therefrom the mixture produced in the hopper.
  5. In an apparatus for concentrating ore and the like, the combination of a hopper of comparatively small volume, means for introducing ore into the hopper, means for introducing a selective agent into the hopper near the point of introduction of the ore, means for introducing a stream of liquid under high pressure into the hopper near the point of introduction of the ore and the selective agent for agitating the same, said hopper being placed to receive the impact of the mixture under the impulse of the liquid stream, and a flotation
- separating receptacle connected to said hopper and adapted to receive by overflow therefrom the mixture produced in the hopper.
6. The process of concentrating ore and the like consisting in introducing the ore and a selective agent into a body of separating liquid from separate sources and agitating the mixture by a stream of liquid under high pressure.
  7. The process of concentrating ore and the like consisting in introducing the ore and a selective agent into a body of separating liquid and mixing and vigorously agitating said liquid, ore, and selective agent by a high velocity stream of liquid only.
  8. The process of concentrating ore and the like consisting in introducing the ore and a selective agent into a body of separating liquid, agitating said ore and selective agent at the point of introduction into the separating liquid by a stream of liquid under high pressure only, said selective agent being delivered into contact with the ore in the agitating region.
  9. The process of concentrating ore and the like consisting in feeding the ore and a selective agent to a body of separating liquid prior to mixing the same, and agitating said ore and selective agent at the point of introduction into the separating liquid by a stream of liquid under high pressure.
  10. In an apparatus for concentrating ore and the like the combination of a hopper of comparatively small volume, means for introducing the ore and a selective agent into the hopper from separate sources, means for introducing a stream of liquid at high velocity into the hopper for agitating the contents of the same, and a flotation separating receptacle connected to said hopper and adapted to receive by overflow therefrom the mixture produced in the hopper.
  11. In an apparatus for concentrating ore and the like the combination of a hopper and a flotation separating receptacle arranged to receive by overflow therefrom the contents of said hopper, means for supplying ore and a selective agent to the separating liquid in said hopper, and means for mixing and agitating the pulp and selective agent in said hopper by a stream of liquid under high pressure.
